UNITED STATES PATENT OFFICE.

ETHAN ROGERS UNDERWOOD AND MICHAEL RUSSO, OF ELIZABETH, NEW JERSEY, AS
SIGNORS TO FULTON SPECIALTY CO., A CORPORATION OF NEW JERSEY.

INKING OR STAMP PAD.

Application filed July 22, 1924. Serial No. 727,428.

This invention relates, generally, to improvements in inking or stamp pads; and, the present invention has reference, more particularly, to a novel construction of inking or stamp pad, with a view of providing a pad in which the various parts are of a construction, and are assembled in such a manner, so that the printing stamp, when applied to the inked surface of the pad, will receive only a minimum amount of ink upon its printing surface, so as to prevent smearing, but still producing a perfectly made and readable impression.

The present invention, therefore, has for its principal object to provide a neat and simply constructed inking or stamp pad of the general character hereinafter more fully set forth, which will produce the above-mentioned results; and, the invention has for its further object to provide an inking or stamp pad in which the ink-absorbing element of the pad, usually of felt, plush, or the like, is superimposed by a flexible and resilient mat-surface of rubber, and preferably suitably perforated, for conveyance of the ink to a surrounding covering, made of muslin, cotton, or any other analogous material, all arranged to thereby produce a soft, flexible and resilient stamp-receiving surface, for properly transmitting the right quantity of ink to the printing surface of the printing stamp, without any danger of smearing, and still producing a clean and clearly printed impression when the stamp is used.

Other objects of the present invention not at this time more particularly enumerated will be clearly understood from the following detailed description of the present invention.

With the various objects of the present invention in view, the said invention consists, primarily, in the novel inking or stamp pad hereinafter set forth; and, the invention consists, furthermore, in the novel arrangements and combinations of the various devices and parts, as well as in the details of the construction of the said parts, all of which will be more fully described in the following specification, and then finally embodied in the clauses of the claims which are appended to, and which form an essential part of the said specification.

The invention is clearly illustrated in the accompanying drawings, in which:

Figure 1 is a perspective view of an inking or stamp pad made according to and embodying the principles of the present invention, a portion of the device being represented as being broken away, and showing a sectional representation of the parts of the pad.

Figure 2 is a similar view of the inking pad, removed from its enclosing box or casing, with the enveloping fabric shell of the pad shown opened up at one end, to more clearly illustrate the general relations of the parts to each other; and Fig. 3 is a vertical sectional representation of the pad, said section being taken on line 3—3 in said Figure 1.

Figure 4 is a perspective view of one form of box or compartment with which the pad is adapted to be used; and Figure 5 is a transverse vertical section, said section being taken on line 5—5 in said Figure 1.

Figure 6 is a part perspective view and part sectional view of a modified form of inking or stamp pad made according to the principles of the present invention.

Similar characters of reference are employed in the said herein-above described views, to indicate corresponding parts.

Referring now to the several figures of the drawings, and more particularly to Figures 1 to 5 inclusive, the reference-character 1 indicates a suitably shaped box or shell, and 2 indicates a cover therefor, which may be suitably hinged to said box or shell, or may be otherwise used in connection therewith. In its base or bottom 3, the said box or shell may be provided with suitably disposed ink-receiving and containing means, in the form of grooves or channels, as 4, preferably arranged in a manner, substantially as indicated in Figure 4 of the drawings. Fitted into this box or shell, and resting upon the base or bottom thereof, and over and above the grooves or channels 4, is the inking pad proper of the device.

This pad, as will be evident from an inspection of the drawings, comprises a member 5 made of felt, plush, or other analogous material, and of suitable thickness so as to properly receive and maintain at all times, the proper quantity of ink, with which it is

adapted to be saturated or impregnated, and suitably mounted upon this member 5 is a second member 6 which is made of rubber, or similar material, having resilient or elastic properties. This member 6 which is provided with a multiplicity of holes or perforations 7, is preferably made somewhat smaller in its dimensions as to width and length, than the corresponding dimensions 10 of the saturated member 5, so as to provide a marginal off-set, as 8, the purpose of which will presently be more fully set forth. The two suitably assembled members 5 and 6 are suitably encased in an envelope or covering 9, of a suitable fabric as muslin, cotton, plush, or other ink-absorbing material. At a corner, as at 10 and as shown in Figure 1, or at any other desired location, the pad proper is suitably made, so as to provide a 15 filling opening or duct, through which the ink from a squirt-can, or otherwise, can be forced into the grooves, or channels 4, when it becomes necessary to re-saturate the member 5 with a new supply of ink.

20 25 In lieu of fitting the inking pad directly into a box 1, as herein-above described, the pad may be cemented directly upon the usual felt-provided surface 11 of the wooden base or support 12, substantially as illustrated in Figure 6 of the drawings, the said base or support being provided with the usual hinged cover 13.

30 35 From the foregoing description of the present invention it will be evident that we have produced a simply constructed inking or stamp pad, which is easily replenished with a fresh supply of ink for the proper saturation of the member 5, and the cushion-member 6 being of rubber, when pressure is applied to the latter in pressing the printing stamp upon the upper surface of the envelope or covering 9, the ink will be forced through the holes or perforations 7 of the member 6 into and through the material 40 45 of which the envelope or covering 9 is made, without smutting the surface of the latter, and without applying an undue amount of ink upon the printing surface of the stamp, that there will be no smearing of the type, and hence at all times a clear impression will be made. Furthermore, the surrounding space formed by the off-set 8 provides a means or space into 50 55 which the ink is also fed by capillary action at the edges of the pad, so that the upper surface of the pad is always sufficiently saturated or impregnated with the ink. And, furthermore, the rubber or other resilient member 6, being compressible, it will 60 65 act as a cushion which protects the envelope or covering against deterioration and the wear and tear of the same, caused by the constant pressure during the many applications of the printing stamp to the inking surface of the device.

Of course we are aware that some changes may be made in the general arrangements and combinations of the several devices and parts, as well as in the details of the construction of the said parts, without departing from the scope of the present invention as set forth in the foregoing specification, and as defined in the clauses of the claims which are appended thereto. Hence, we do not limit our present invention to the exact arrangements and combinations of the several devices and parts as described in the said specification, nor do we confine ourselves to the exact details of the construction of the said parts, as illustrated in the accompanying drawings.

We claim:

1. A stamp-pad comprising an absorbing material adapted to be impregnated with ink, a pressure-receiving cushioning element 25 of rubber super-imposed upon said absorbing material, and an inking stamp-receiving element mounted upon said cushioning element.

2. A stamp-pad comprising an absorbing material adapted to be impregnated with ink, a pressure-receiving cushioning element of rubber super-imposed upon said absorbing material, said cushioning element being provided with a multiplicity of ink-conducting perforations, and an inking stamp-receiving element mounted upon said cushioning element.

3. A stamp-pad comprising an absorbing material adapted to be impregnated with ink, a pressure-receiving cushioning element super-imposed upon said absorbing material, said cushioning element being smaller in breadth and length than the breadth and length of the absorbing material, so as to provide a surrounding ink-receiving space, and an inking stamp-receiving element in which said absorbing material and cushioning element are encased.

4. A stamp-pad comprising an absorbing material adapted to be impregnated with ink, a pressure-receiving cushioning element super-imposed upon said absorbing material, said cushioning element being smaller in breadth and length than the breadth and length of the absorbing material, so as to provide a surrounding ink-receiving space, said cushioning element being provided with a multiplicity of ink-conducting perforations, and an inking stamp-receiving element 120 in which said absorbing material and cushioning element are encased.

5. A stamp-pad comprising an absorbing material of felt adapted to be impregnated with ink, a pressure-receiving cushioning element of rubber super-imposed upon said felt-material, and an inking stamp-receiving element mounted upon said cushioning element.

6. A stamp-pad comprising an absorbing

material of felt adapted to be impregnated with ink, a pressure-receiving cushioning element of rubber super-imposed upon said felt-material, said cushioning element being 5 provided with a multiplicity of ink-conducting perforations, and an inking stamp-receiving element mounted upon said cushioning element.

7. A stamp-pad comprising an absorbing material adapted to be impregnated with ink, a pressure-receiving cushioning element of rubber super-imposed upon said absorbing material, and an inking stamp-receiving element mounted upon said cushioning element, combined with a box into which the stamp-pad is fitted, and an ink-receiving and maintaining means within said box for feeding ink to said pad.

8. A stamp-pad comprising an absorbing material adapted to be impregnated with ink, a pressure-receiving cushioning element of rubber super-imposed upon said absorbing material, said cushioning element being provided with a multiplicity of ink-conducting perforations, and an inking stamp-receiving element mounted upon said cushioning element, combined with a box into which the stamp-pad is fitted, and an ink-receiving and maintaining means within said box 30 for feeding ink to said pad.

9. A stamp-pad comprising an absorbing material adapted to be impregnated with ink, a pressure-receiving cushioning element super-imposed upon said absorbing material, 35 said cushioning element being smaller in breadth and length than the breadth and length of the absorbing material, so as to provide a surrounding ink-receiving space, and an inking stamp-receiving element in which said absorbing material and cushioning element are encased, combined with a box into which the stamp-pad is fitted, and an ink-receiving and maintaining means within said box for feeding ink to said pad.

45 10. A stamp-pad comprising an absorbing material adapted to be impregnated with ink, a pressure-receiving cushioning element super-imposed upon said absorbing material, said cushioning element being smaller in 50 breadth and length than the breadth and

length of the absorbing material, so as to provide a surrounding ink-receiving space, said cushioning element being provided with a multiplicity of ink-conducting perforations, and an inking stamp-receiving element in which said absorbing material and cushioning element are encased, combined with a box into which the stamp-pad is fitted, and an ink-receiving and maintaining means within said box for feeding ink to 60 said pad.

11. A stamp-pad comprising an absorbing material adapted to be impregnated with ink, a pressure-receiving cushioning element super-imposed upon said absorbing material, 65 said cushioning element being smaller in breadth and length than the breadth and length of the absorbing material, so as to provide a surrounding ink-receiving space, and an inking stamp-receiving element in 70 which said absorbing material and cushioning element are encased, combined with a box into which the stamp-pad is fitted, said box being provided in its base with ink-receiving and maintaining channels, and 75 means for feeding ink to said channels.

12. A stamp-pad comprising an absorbing material adapted to be impregnated with ink, a pressure-receiving cushioning element super-imposed upon said absorbing material, 80 said cushioning element being smaller in breadth and length than the breadth and length of the absorbing material, so as to provide a surrounding ink-receiving space, said cushioning element being provided with 85 a multiplicity of ink-conducting perforations, and an inking stamp-receiving element in which said absorbing material and cushioning element are encased, combined with a box into which the stamp-pad is 90 fitted, said box being provided in its base with ink-receiving and maintaining channels, and means for feeding ink to said channels.

In testimony, that we claim the invention 95 set forth above we have hereunto set our hand this 18th day of July 1924.

ETHAN ROGERS UNDERWOOD.
MICHAEL RUSSO.
